TOY

Marvin I. Glass, Chicago, and Leonid Kripak, Villa Park, Ill.; said Kripak assignor to said Glass
Filed July 24, 1959, Ser. No. 829,422
4 Claims. (Cl. 46—1)

This invention relates to the carrying of toy weapons, such as a pistol, and more particularly, to a toy pistol which is carried by the forearm and which can be suddenly positioned in the hand ready for firing from a concealed position along the inner forearm.

The principal object of the invention is a toy weapon which incorporates means affording carrying of the toy weapon on the body. Another object of the invention is a toy weapon which can be worn either on the left or right forearm and which is swingable between a concealed position along the inner forearm to a firing position in the hand. A further object of the invention is the provision of a toy pistol which incorporates the features mentioned above and which is economical in construction and simple in operation. A still further object of the invention is the provision of a hinged holding device for carrying toy weapons. Other objects and advantages of this invention will be understood by reference to the following description, and to the accompanying drawings in which:

FIGURE 1 is a perspective view of a toy pistol embodying various features of the invention. The pistol is shown carried by the forearm in concealed position;

FIGURE 2 is a perspective view similar to FIGURE 1 showing the pistol in the hand;

FIGURE 3 is an enlarged side view, partially broken away, of a portion of FIGURE 1;

FIGURE 4 is a sectional view taken generally along line 4—4 of FIGURE 3;

FIGURE 5 is a view similar to FIGURE 4 showing the hinge connected to the pistol in open position;

FIGURE 6 is an enlarged perspective view, partially broken away, showing parts of the hinge in exploded condition; and

FIGURE 7 is a perspective view, partially broken away, illustrating an arrangement for detachably securing the toy weapon to the hinge.

Basically, a combination in accordance with the invention includes a toy weapon, such as the pistol 11 which is carried by one leaf or element 13 of a hinge. The other leaf or element 15 includes means for fastening the hinge to the forearm so that the gun is swingable between a concealable position along the inner forearm to a firing position in the hand. In the embodiment shown in FIGURES 1 and 2, the hinged elements 13 and 15 are maintained in closed position, as seen in FIGURE 1, by means of a latch 19 and are biased toward the open position, as seen in FIGURE 2, under action of a spring 23. The latch 19 is releasable by manipulation of the hand with a latch trigger 21 to unexpectedly swing the pistol into the hand ready for firing.

The hinge element 13 is generally of channel formation having a web 25 and a pair of flanges 27 which include at one end a pair of apertured ears 29 receiving a hinge post 31. Carried at the other or free end of the hinge element 13 by suitable means, such as screws 33, is the pistol 11. Preferably, the pistol 11 includes a cap firing mechanism but is small in size so as to be concealable by the forearm. Of course, numerous other toy weapons could be carried by the disclosed holder including, for example, a water pistol, a rubber knife blade, etc.

The other hinge element 15 comprises a channel-shaped member 35 having a pair of flanges 37 which extend

2

from a web 39 and include a pair of forwardly located apertured ears 41 receiving the hinge post 31, thereby swingably connecting the two hinged elements together. The channel-shaped member 35 also includes a pair of laterally extending flanges 43 to which a plate 45 is secured by suitable means, such as rivets 47, to provide a rectangular guide-way in which a part of the latch is slidably contained.

While various arrangements can be employed to fasten the hinge element 15 to the forearm, in the disclosed construction, the hinge element 15 is connected to the wrist and adjoining forearm by an elongated gauntlet or wristband 49 which is preferably fabricated from a flexible material, such as leather or plastic. Suitable means, such as the illustrated series of belts 51 and buckles 53, are incorporated in the gauntlet for detachably securing it to the arm. As shown, the hinge element 15 is secured to the gauntlet 51 by the rivets with the forward or hinge post end of the hinge element 15 disposed along the forward end of the gauntlet.

As previously mentioned, the hinge elements 13 and 15 are maintained in their closed position, as shown in FIGURES 1, 3, and 4, against the action of the spring 23, by means of the latch 19. The latch constitutes a hook 53 carried by the hinge element 13 and a slide 55 which includes the trigger 21 and is carried in a guide-way formed by the hinge element 15 for engagement with the hook 53. As shown, the hook 53 includes a camming surface 54 to assist in interengagement of the slide as will be more fully described.

The slide 55 includes a main portion of channel-shaft formation having a top face 59, side flanges 61 and an end wall 63. Located centrally in the face 59 is a hole admitting opening 65 which is bounded on one side by a transversely disposed tab 67 extending upwardly and rearwardly for camming action with the hook 53 during engagement of the latch.

The face 59 and a portion of the end wall 63, as particularly in FIGURE 6, are also apertured as indicated at 69 to permit insertion of a part of the spring between the slide 55 and the plate 37. Extending rearwardly from the end wall 63 is the latch trigger 21 which constitutes a flat arm 71 having at its outer end an inwardly directed flange 73. This flange is contacted by the slide 55 to move the slide rearwardly by the base of the hand to effect release of the latch. The flange 73 also functions to limit opening movement of the hinge element 13 relative to the hinge element 15 when these elements are roughly in co-planar relationship.

The spring 23, which urges the hinged elements to open position, is formed of spring wire and is carried on the hinge post 31. One end 75 of the spring 23 is in engagement with the under surface of the hinge element 15, as seen particularly in FIGURES 4 and 6. The other end 76 extends inwardly of the hinge element 15, between the slide 55 and the plate 37, to urge the hinge elements away from the element 13. This end 76 is formed with a flat coil 77 having a portion 78 which bears against the inner surface of the slide end wall 63 to bias the slide rearwardly, thereby retaining the slide in engagement with the hook 53. Thus, the spring 23 serves the two-fold function of urging the hinged elements apart and assisting in retaining them in locked condition.

When the gauntlet 49 carrying the hinge elements 13 and 15 is secured to the forearm and when the hinged elements are in latched closed position, the pistol 11 is carried in concealed position on the inner side of the forearm. The latch trigger 21 extends forwardly, relative to the hinge post to a position at the base of the hand. A slight movement of the hand toward the body will push the slide rearwardly thereby releasing the latch and permitting

the spring to swing the hinge elements open, thereby suddenly placing the gun in the hand for firing.

The pistol can be returned to its concealed position by a quick rearward movement of the arm. Such movement causes the pistol carrying hinge element 13 to swing about the hinge post 31 into closed position. In this connection, the slide 55 is urged rearwardly to permit passage of the hook 53 through the opening 65 in the slide 55 by engagement of the camming surface 54 with the tab 67. When movement of the hook 53 through the opening 65 is completed, the slide again moves forwardly to engage the hook, thereby retaining the hinged elements in closed position.

As shown in FIGURE 7, the hinge element 13 and the pistol 11, or other toy weapon, can be constructed for detachable assembly to permit use of the holder with several different toy weapons and to allow use of the holder on either the right or left arm. While these features can be realized through various connecting arrangements in the disclosed construction, they are provided by a detachable connection 79 which includes a socket 81 in the butt of the pistol and a male prong 83 which extends from the hinge element 13 and is insertable within the socket 81.

The prong 83 is constructed, in cooperation with the socket 81, to permit inverted assembly of the pistol with the hinge element 13, thereby accommodating both left and right hand usage, and to prevent pivoting of the pistol about an axis extending along the prong. These features are achieved by forming the prong 83 with a generally cross-shaped cross-section which includes pairs of vertical and horizontal vanes 87 and 89 and by forming the socket 81 with a mating cross-section. Locking engagement of the prong 83 with the socket 81 is provided by a catch 91 which includes a locking pin in the pistol and an arcuate cut-out or notch 95 in each of the vertical vanes 87.

The locking pin is carried transversely in the pistol butt and comprises a shaft 97 having a head 99. The shaft 97 includes a groove 101 which can be aligned with the vertical vanes 87 and is of sufficient depth to permit passage of the unnotched portion of the adjacent vertical vane. The pistol 11 is locked to the hinge element 13 through the operation of a spring 103 which carries the shaft 97 into a position of misalignment between the vertical vanes 87 and the groove 101, thereby engaging the notch 95 by the shaft 97. Of course, the pistol can be removed from the hinge element 13 by inwardly pressing the head of the pin to align the groove 101 with the vertical vanes 87, and then by withdrawing the prong 83 from the butt of the pistol.

The novel toy disclosed herein provides quick and unexpected delivery of a weapon from a concealed position on the forearm to a position in the hand ready for use. This surprise action takes place in response to a hardly noticeable manipulation of the hand. In addition, the weapon is readily returnable to its concealed position by means of a quick rearward arm movement. These action features result in a highly entertaining and desirable toy novelty.

Various features of the invention are set forth in the appended claims.

We claim:

1. A toy adapted to be carried on the forearm of a user and effective upon actuation thereof to cause a toy pistol to move from a position adjacent the forearm to a position in the hand, said toy comprising a first and a second element hingedly interconnected so as to permit relative movement thereof between an open and a closed position, a toy pistol rigidly attached to said first element, means for attaching said second element to the forearm such that hinged movement of the first of said elements relative to the second of said elements is effective to place said pistol in the hand of the user, means spring biasing said hinged elements into said open position, releasable

latch means effective to maintain said hinged elements in said closed position, and release means connected to said latch means and operable when actuated to release said latch means.

5. 2. A toy adapted to be carried on the forearm of a user and effective upon actuation thereof to cause a toy pistol to move from a position adjacent the forearm to a position in the hand, said toy comprising a first and a second element hingedly interconnected so as to permit relative movement thereof between an open and a closed position, a toy pistol rigidly attached to said first element, means for attaching said second element to the forearm such that hinged movement of the first of said elements relative to the second of said elements is effective to place said pistol in the hand of the user, spring biasing said hinged elements into said open position, releasable latch means effective to maintain said hinged elements in said closed position, and means connected to said latch means and operable when actuated to release said latch means, said release means being operable by a predetermined movement of the hand, whereby such movement of the hand results in the actuation of said latch means, thereby permitting swing movement of the elements to said open position under the influence of said biasing means and thereby carrying said pistol from its concealed position to a position in the hand ready for use.

3. A toy adapted to be carried on the forearm of a user and effective upon actuation thereof to cause a toy pistol to move from a position adjacent the forearm to a position in the hand, said toy comprising a first relatively rigid element, fastening means attached to said first element and adapted to secure said first element to the forearm, a second relatively rigid element pivotally attached at one end thereof to the end of said first element nearest the hand for swinging movement of said second element relative to said first element between a closed position and an open position with said second element extending toward the hand, a toy pistol, means mounting said toy pistol on said second element in a position that said pistol lies in the hand when said second element is in its open position, means spring biasing said elements toward said open position, latch means carried by said elements for releasable engagement to hold said elements in said closed position, and release means connected to said latch means and operable when actuated to release said latch means, said release means being positioned to be operable by an inward movement of the hand at the wrist, whereby such movement of the hand results in the release of said latch means, thereby permitting swinging movement of said elements to said open position under the influence of said biasing means and thereby carrying said pistol from its concealed position to a position in the hand ready for use.

4. A toy adapted to be carried on the forearm of a user and effective upon actuation thereof to cause a toy pistol to move from a position adjacent the forearm to a position in the hand, said toy comprising an elongated wristband including fastening means adapted to be carried by said wristband to the forearm, a first element fixedly carried by said wristband with one end thereof adjacent the forward end of said wristband, a second element pivotally carried at one end thereof on said one end of said first element for swinging movement of said second element relative to said first element between a closed and an open position, a toy pistol, means detachably connecting said toy pistol and the other end of said second element in either of two positions which are inverted with respect to each other so as to accommodate use on either the right or left forearm, means biasing said elements toward said open position, and latch means carried by said elements for releasable engagement to hold said elements in said closed position, said latch means including a slide carried by said first element and a hook carried by said second element, said slide being urged by said biasing means in

leasable engagement with said hook, thereby maintaining said elements in closed position, said slide including a trigger part extending forwardly of the forward end of said wristband for engagement by the base of said hand to effect release of the engagement between said slide and said hook, thereby permitting swinging movement of said elements to said open position under the influence of said biasing means and thereby carrying said pistol from its concealed position to a position in the hand ready for use.
